UNITED STATES PATENT OFFICE.

WALTHER KUNDE, OF DRESDEN, GERMANY.

HOLDER FOR WRITING AND SIMILAR INSTRUMENTS OR TOOLS.

No. 901,452.

Specification of Letters Patent.

Patented Oct. 20, 1908.

Application filed November 4, 1907. Serial No. 400,540.

To all whom it may concern:

Be it known that I, WALTHER KUNDE, a subject of the German Emperor, residing at Dresden, in Germany, have invented a certain new and useful Holder for Writing and Similar Instruments or Tools, of which the following is a specification.

This invention relates to an improved flexible attachment for writing and similar instruments adapted to be suitably fixed where required for instance on or adjacent a telephone-desk, shop-cash-desk or counter, type-writing machine table, or writing-table, etc. Instead of a pencil there may be suspended on the attachment any other office article of use, such as india-rubber, sealing wax, color-pencil, etc., or it may accommodate tools or the like which may be required at the place or point where the work is taking place.

The improved attachment is represented in elevation in the accompanying drawing.

f is a vertically socketed foot piece. In the foot *f* is inserted the helically wound stem which may be formed of metal wire and has the coils lying closely together for the greater part of its length but as to the remainder of its length spaced apart to its up-

per end, this upper part is also curved in general direction so that the pencil or other object hangs freely away from the attachment. A cord, chain or the like *k* passes through the coils and extends through a cap *h* and to said cord is suspended the pencil *b* or other desired object.

What I claim as my invention and desire to secure by Letters Patent of the United States is:—

A holder for writing instruments and other objects comprising in combination a vertically socketed foot piece, a helically wound upright projecting vertically above said foot piece and formed with closely lying convolutions for the greater part of its length and more widely spaced convolutions for the remainder, the latter part being also curved away from the perpendicular, and a flexible member traversing said upright and extending beyond the end thereof for attachment of the article thereto.

In witness whereof I have signed this specification in the presence of two witnesses.

WALTHER KUNDE.
